UNITED STATES PATENT OFFICE.

EARL A. DILLON, OF SAN ANTONIO, TEXAS.

TURNTABLE.

Application filed September 3, 1927, Serial No. 217,409. Renewed November 19, 1928.

This invention relates to turntables and is an improvement upon the subject matter disclosed in my co-pending application Serial No. 150,926, filed November 26, 1926.

Like the invention referred to, the present invention has for its object the provision of a turntable for automobiles, for use in garages and other restricted places, such as warehouses, depots and the like.

The primary object of the invention is to improve and simplify the turntable disclosed in the application mentioned, by reducing the number of parts and providing means of adjustment for the turntable platform to insure ease of rotation, and to especially provide means for controlling the operation of the turntable by the direction of rotation of the wheels of an automobile, so that the driver will not be required to manually release or apply the turntable brakes.

With the above and other objects in view, the invention further includes the following novel features and details of construction, to be hereinafter more fully described, illustrated in the accompanying drawings and pointed out in the appended claims.

In the drawings:

Figure 1 is a top plan view of a turntable constructed in accordance with the invention.

Figure 2 is a bottom plan view of the turntable platform.

Figure 3 is a section on the line 3—3 of Figure 1.

Figure 4 is a fragmentary bottom plan view of the circular track and its manner of connection with the center bearing.

Figure 5 is an enlarged fragmentary section taken substantially on the line 5—5 of Figure 1 with the roller cover plate swung downward so as to render the rollers inactive.

Figure 6 is a like view showing the rollers uncovered.

Figure 7 is an enlarged fragmentary section taken substantially on the line 7—7 of Figure 1.

Referring to the drawings in detail where-in like characters of reference denote corresponding parts, the turn-table is mounted within a suitable pit 10 and its platform 11 is flush with the floor or surface 12 which surrounds the pit. The platform 11 is supported by a central bearing 13 and by rollers

14 which are spaced around and secured to the under face of the platform 11.

The rollers 14 operate upon a track 15 and the latter is substantially L-shaped in cross section so as to provide a vertically disposed circular flange 16. The center bearing 13 is formed of opposed bearing members 17 and 18, the former being secured to the inner ends of radially disposed arms 19. The outer ends of these arms are secured to the track 15 as shown at 20 and not only serve to secure the bearing member 17 in place, but also serve to assemble the track 15, the latter being formed of segmental sections. The bearing member 17 is provided with a seat or depression 21 to receive an anti-friction ball 22. The bearing member 18 is secured to the under face of the platform 11 and is provided with a recess 23 within which is movably located a bearing block 24. This block is provided with a seat or depression to receive the ball 22 while an adjusting screw 25 extends through the platform and bearing member 18 and engages the bearing block. By means of the screw 25, the block 24 may be adjustably positioned so as to properly distribute the weight of the platform to insure ease of operation, as will be hereinafter apparent.

Secured to the upper face of the platform 11 are spaced channel shaft tracks or guides 26. These guides are provided with openings which register with openings 27 provided in the platform for the accommodation of rollers 28 and 29. These rollers are arranged in pairs as shown in the drawings, one pair being located at one end of each guide 26. These rollers control the operation of the turntable and the mechanism controlled by these rollers is duplicated upon 95 diametrically opposite sides of the center bearing. This mechanism is clearly shown in Figure 2 of the drawings and only one of such mechanisms will be described. The

shaft 30 of the roller 28 is mounted in suitable bearings 31 secured to the under face of the platform 11 and this shaft carries a beveled pinion 32 which engages and drives a beveled pinion 33 mounted upon a shaft 34. This last mentioned shaft is journaled in suitable bearings attached to the under face of the platform and has secured thereon a beveled pinion 35. The pinion 35 engages the teeth of a rack 36 provided around the upper edge of the flange 16 and when the

roller 28 is rotated, rotary movement will be imparted to the platform. The adjustment of the center bearing 13 is especially useful for properly distributing the weight of the 5 platform to insure proper working engagement between the pinions 35 and the rack 36.

The shaft 37 of the roller 29 is mounted in suitable bearings 38 secured to the under face of the platform 11 and secured upon 10 this shaft 37 is a brake drum 39. A brake band 40 is arranged to engage the outer periphery of this drum and has one of its ends anchored as at 41. The other end of the band 40 is pivotally secured as at 42 to 15 one end of a weighted arm 43, the said arm being pivotally mounted as shown at 44. The tendency of the weighted arm 43 is to apply sufficient friction to the drum 39 to prevent accidental rotation of the roller 29.

20 Pivottally mounted within each guide adjacent each of the rollers 29 as shown at 45, is a cover plate 46. This cover plate is normally held in elevated position by means of a weight 47, as shown in Figure 6 of the 25 drawings, but is capable of being swung down into position to cover the rollers 28 and 29, as shown in Figure 5.

An automobile driven upon the platform will travel along the guides 26, one of the 30 front wheels of the automobile riding upward over the rollers 28 and 29. The roller 28 will be momentarily partially rotated, but this rotation will not be enough to cause rotary movement of the platform. Continued 35 forward movement of the automobile will force the cover plate downward so as to permit the wheel to ride over the plate. One of the rear wheels of the automobile will ride over the roller 28 and occupy a position 40 over this roller and the roller 29 as shown in Figure 6 of the drawings. The transmission mechanism of the automobile is put in reverse and when the rear wheel is rotated, the rollers 28 and 29 will be rotated 45 in the direction indicated by the arrows in Figure 6. As the weight of the arm 43 tends to tighten the brake bands 40, rotation of the roller 29 in the direction indicated by the arrow in Figure 6 and opposite to the 50 direction indicated by the arrow in Figure 7, will tend to release this brake band and permit free rotation of the roller 29. As the roller 28 is rotated, rotary motion will be imparted to the platform 11 through the 55 gearing previously described. After the platform has been turned to the desired position, operation of the rear driving wheel of the automobile is stopped. The transmission is then shifted so that the automobile 60 may be driven forward, whereupon the tend-

ency of the roller 29 will be to rotate in the direction indicated by the arrow in Figure 7. The brake band will thus have a tendency to tighten and prevent rotation of the roller 29, so that the automobile may be 65 driven from the rollers. Forward movement of the automobile will press the cover plate 46 downward upon the platform, while the opposite front wheel of the automobile will press the other cover plate downward so as to cover the rollers 28 and 29 and 70 permit the automobile to pass over these rollers without rotating the latter.

The invention is susceptible of various 75 changes in its form, proportions and minor details of construction and the right is herein reserved to make such changes as properly fall within the scope of the appended claims.

Having described the invention what is 80 claimed is:—

1. In combination with a turntable, a 85 brake mechanism, means operated by the wheels of an automobile when said wheels are rotating in one direction to simultaneously release the brake mechanism and rotate the turntable and means rendered active when the automobile wheels are rotating in an opposite direction to lock the turntable 90 against rotary movement.

2. In combination with a turntable, mechanism to rotate said table, spaced rollers carried by the turntable for engagement by the drive wheels of an automobile, a brake mechanism, means associating one of the rollers with the turntable rotating mechanism to 95 operate the latter when the rollers are rotated in one direction and means connecting the other roller and brake mechanism to release the said brake mechanism when the drive wheels are rotating in the referred to 100 direction and to render the brake mechanism active when said wheels are rotating in an opposite direction.

3. In combination with a turntable, means 105 to rotate the turntable, spaced means operated by the wheels of an automobile to control the turntable rotating means, and means operated by the wheels of the automobile to selectively render one of the wheel operated means inactive.

4. In combination with a turntable, means to rotate the turntable, spaced means operated by the wheels of an automobile to control the turntable rotating means and pivotally mounted cover plates located in the 115 path of the wheels of the automobile to selectively cover the wheel operated means.

In testimony whereof I affix my signature.

EARL A. DILLON.
